United States Patent Office.

GEORGE W. BISHOP, OF BALTIMORE, MARYLAND.

Letters Patent No. 83,127, dated October 20, 1868; antedated October 6, 1868.

REVENUE-STAMP FOR LIQUOR-BARRELS.

The Schedule referred to in these Letters Patent and making part of the same.

To all whom it may concern:

Be it known that I, GEORGE W. BISHOP, of Baltimore, in the county of Baltimore, and in the State of Maryland, have invented certain new and useful Improvements in Revenue-Stamps for Liquor-Barrels; and do hereby declare that the following is a full, clear, and exact description thereof, reference being had to the accompanying drawings, and to the letters of reference marked thereon, making a part of this specification.

Figure 1 represents an oblong metal plate, which is used under the stamp;

Figure 2 represents a view of the under part of the device;

Figure 3 represents a plan view of the same with the slide extracted;

Figure 4 represents a horizontal section;

Figure 5 represents a cross-section, taken through the longitudinal centre;

Figure 6 represents a view of the stamp which receives the impression of the die;

Figure 7 represents a plan view; and

Figures 8 and 9 are printed blank forms, which are used by the inspector.

My invention is intended for use upon liquor-barrels, and to be placed over the bung, so as to prevent fraud on the revenue.

In the annexed drawings, A represents a narrow oblong metallic plate, the under part of which is slightly taken off, as seen in fig. 4, so that it may conform to the central bulge of the barrel. The centre of this plate, on the top face, is formed into an oblong square box, B, as shown. Both of the upper sides of plate A are slightly raised, and are so bevelled as to form narrow flanges for securing a flat metallic slide, D, which extends the entire length of the plate and under the central box B.

a a represent screw-holes for connecting the plate A to the barrel, which connection is made prior to the insertion of the slide D.

z z z represent small holes in the under part of the box A, through which pins are passed. Like holes are made in the centre of the slide, which correspond with the holes in the box.

This plate, with its box and slide, may be cast of any suitable metal, and is intended to be used only upon one barrel.

C represents the impression-stamp. This stamp is made of lead, or other equivalent soft metal, and is provided with pins b b b, which project downwards, as seen in fig. 6. These pins are provided with suitable heads, and the lead or other metal is cast or forced around said heads, to prevent them from becoming extracted from the stamp. This stamp is made to fit neatly in the box B, which box is bevelled from top to bottom on its four sides, (see d, figs. 4 and 5), so

that after the stamp is placed within it and the die impressed on its top by the revenue officer, the metal will be forced under the bevelled edges, and rigidly held in the box.

Under the box B there is a small space, within which is placed a short metal plate, g, and which lies directly over the bung, and under a narrow horizontal groove, z, fig. 2, made where the ends of the pins z z pass through.

This device is connected to the barrel, with the box B, directly over the bung, and a printed blank, i i, put in a space each side of the box. The slide is then fitted into the grooves, and the stamp C is then placed into the box, with the pins b b passing through the box and slide D, the ends thereof resting on the metal plate g.

After the officer has made the inspection, and recorded it on the duplicate blanks, and affixed the slide D, the impression is made on the stamp, which forces the metal of the stamp under the edges of its box, and at the same time turns the ends of pins upon the metal plate g, and causes them to lie in the groove z, so as to effectually prevent the extraction of the stamp.

Upon the printed blanks i i, which lie under the slide D, are placed the date of inspection, the lot-numbering, from one to ten, or other number, number of gallons in the lot, the tax paid, and the number of the barrel, and any other matter desired. On the back of the form is the name of the inspector, his district, and State.

It will be understood that the bung cannot be taken from the barrel without the stamp herein described is first taken off, or the stamp obliterated. The slide being over the screw-holes, cannot be taken off, hence it becomes necessary to destroy it when the dealer desires to open the bung. This is done by cutting (with a chisel or other instrument) each side of the box B through the stamp. The dealer then can extract the bung and the stamp, and will retain one of the forms, i, and transmit the other to the revenue office of the United States. The one he retains is his voucher to show that the tax has been paid, and the other one, that he forwards, is a voucher against the officer who has collected the revenue.

I may shorten the plate A, and use my device for covering spicket-holes. In that case there would be no forms used.

The officer marks each barrel with a stencil or other plate, and places a check or form, i, with a number to correspond with the number marked on the barrel, so that the check can be used for that barrel alone.

My invention obviates the necessity of destroying the barrel after once used, as is now the practice. I only destroy the stamp.

Having thus fully described my invention,

What I claim, and desire to secure by Letters Patent, is—

1. The oblong plate A, provided with flanges on the sides, and with a central box, B, when constructed substantially as and for the purposes specified.
2. The "stamp" C, made of soft metal, and provided with pins b b, as described, and used with the bevelled box B, substantially as set forth.
3. The combination of the perforated slide D with

the box B in the plate A, and stamp C, when used as and for the purposes specified.

4. The forms i i', placed in the plate A under the slide D, as and for the purposes specified.

In testimony that I claim the foregoing, I have hereunto set my hand, this 26th day of February, 1868.
